UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

APPARATUS FOR REFINING MINERAL OILS.

1,335,773.

Specification of Letters Patent. Patented Apr. 6, 1920.

Application filed January 21, 1918. Serial No. 212,950.

To all whom it may concern:

Be it known that I, FRANK E. WELLMAN, a citizen of the United States, residing at Kansas City, in the county of Wyandotte 5 and State of Kansas, have invented certain new and useful Improvements in Apparatus for Refining Mineral Oils, of which the following is a specification, reference being had therein to the accompanying drawing.

10 My invention relates to oil refining apparatus and especially to apparatus for treating mineral oils under high temperature and high pressure and controlling means therefor.

15 The present invention is a continuation in part of my copending application Serial No. 110,794, filed July 22, 1916, in which I have described a combination of apparatus for use in cracking mineral oils under high temperature and high pressure with certain 20 safety appliances found to be necessary in the use of said apparatus, especially where high temperatures and high pressures are to be employed.

25 My invention is illustrated in the accompanying drawing which shows in diagram a structure and arrangement of apparatus embodying the preferred form of my invention.

30 Referring to the drawing in particular, 12 indicates a receiving tank into which discharges a feed pipe 11 leading from a suitable source of supply of the hydrocarbon to be cracked. From the feed tank 12 extends 35 a suction pipe 13 to the pump 14. From the pump a discharge pipe 15 is carried to the superheater 16, in which discharge pipe are connected an automatic check valve 17, a normal relief valve 18, and an automatic 40 cut-off valve 10. The coil of the superheater is expanded at the intake head 16^a to a diameter greater than the pipe line 15. From the outlet head 16^b an extension pipe 19, of the same diameter as the superheater 45 is carried to the precooler 20 and extends through said precooler without any reduction in its diameter. The precooler may be of any desired form, but in practice I employ an iron tank in which water is caused 50 to circulate and which is made large enough to accommodate a number of coils of smaller pipe 21, for example 1 inch pipe, from the relief valve 18. This or an equivalent provision for cooling the relief pipe 21 is absolutely necessary in practice in order to

prevent the destructive effect of oil suddenly discharged into the atmosphere at high temperature and high pressure. The valve 18 is a three-way valve arranged to close the connection with the pipe 15 and 60 connect the coil 16 with the relief pipe 21 in emergency, but normally closing the relief passage and connecting the pipe 15 with the superheater coil. The purpose of this is to prevent additional vapor being forced 65 into the superheater coil, after a break occurs in the latter, which would otherwise add fuel in a dangerously heated condition, to any fire already started.

As the use of the relief valve 18 is usually 70 necessary at a time when there is some danger to the operator, it is desirable to have it controlled from a distance and to be certain in operation. To this end, instead of the usual hand wheel, the valve stem is turned 75 by a lever 30 fixed thereto provided with a counterweight 31 tending to swing the lever to open the valve, and a latch 32 for holding the lever in its normal position against the tension of the weight. This latch is 80 pivoted at 33 and is arranged to be operated from a distance by means of the pull cord 34 attached thereto at a point above the pivot so as to pull the latch out of engagement with the arm. A suitable retractile 85 spring 35 is provided for holding the latch in engagement with the valve lever. Similarly the high pressure controlling valve 25 is in practice provided with a drum 36 fixed to the valve stem in place of the usual hand 90 wheel, and on this drum is coiled a cord or cable 37 which leads to a distant point so that the valve may be opened and closed without approaching the superheater, the drum being provided with a retracting cord 95 38 wound on the hub 39 and tensioned by a weight 40, so that the drum 36 may be rotated in opposite directions by pulling and releasing the operating cord 37. For further safety I insert a check valve 22 in the 100 pipe 19 leading into the precooler 20. This check valve acts in case of an emergency to prevent oil or vapor from such segregating and receiving apparatus as may be connected with the pipe 23 from flowing back into 105 the superheater. In normal operation the overflow of cracked products from the superheater coil through the pipe 23 is regulated by the high pressure controlling valve 25. The valve 10 inserted in the pipe line 110

15 between the pump 14 and the check valve 17 is an automatic valve operable upon a decrease in pressure in the superheater coil 16 to close communication between said coil 5 and the tank 12 until the pump can be shut down. This valve may be of any known type of regulating valve responsive to changes in pressure and may, as shown, consist generally of a globe valve 41 having its 10 valve stem 42 operated by a diaphragm 43 connected with the diaphragm chamber 44, which chamber may be connected through a suitable pressure line 45 to the pipe line 15, as shown, or any part of the apparatus in 15 which the pressure is the same as that in the superheater.

In operation, the receiving tank 12 being supplied from a suitable source with hydrocarbon to be cracked, the pump 14 is started, and the superheater coil 16 is partially filled with the material and heat is started in the furnace of the superheater. With the high pressure controlling valve 25 closed, the temperature of the superheater is raised 20 and at the same time the pump 14 is kept working to increase the pressure, until sufficient cracking commences. The valve 25 is 25

then manipulated so as to start an overflow of the cracked product through the pipe 23 to suitable segregating and receiving apparatus not shown, which operation is thereafter carried on continuously, the temperature being maintained at about 700° F. or over and the pressure at approximately 200 pounds, the valves 18 and 25 being controlled as and for the purposes above described. 30

Having thus described my invention what I claim and desire to secure by Letters Patent is— 35

In a system for cracking hydrocarbon oil, a cracking coil of large diameter, feed and discharge pipes of smaller diameter, a pressure valve at the discharge end of said cracking coil, and a safety discharge valve at the 40 intake end of the cracking coil, said valves both having cooling coils, that on the pressure valve being of the same diameter as the cracking coil, and that on the safety discharge being the same diameter as the intake pipe. 45

50 In testimony whereof I affix my signature.

FRANK E. WELLMAN.
